(57) **CLAIM**

The ornamental design for a projector for cellular phone, as shown and described.

DESCRIPTION

FIG. 1 is a top, front, and left side perspective view of a projector for cellular phone showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top, front perspective view thereof, showing the secure member in an opened position; while the broken lines showing the cellular phone are included for illustrative environmental structure which form no part of the claimed design. The broken lines showing portions of a projector for cellular phone are included for illustrating environmental structure and form no part of the claimed design.
